UNITED STATES PATENT OFFICE.

ROLAND BENTLEY, OF DRESDEN, AND THOMAS FORD, OF LONGTON,
COUNTY OF STAFFORD, ENGLAND.

CUT-OFF VALVE.

SPECIFICATION forming part of Letters Patent No. 380,474, dated April 3, 1888.

Application filed May 31, 1887. Serial No. 239,801. (No model.) Patented in England June 8, 1885, No. 6,897, and in Belgium September 25, 1886, No. 74,641.

To all whom it may concern:

Be it known that we, ROLAND BENTLEY, of Dresden, in the county of Stafford, England, and THOMAS FORD, of Longton, in the county 5 of Stafford, England, have invented a new and Improved Cut-Off Valve, of which the following is a full, clear, and exact description.

Our invention relates to an equilibrium slide-valve for steam, air, and water engines, 10 with an automatic variable cut-off or expansion valve applicable to steam and air engines.

This invention consists of an equilibrium hollow cylindrical slide-valve worked by an eccentric from the main shaft, as in the ordinary way, with cylindrical valve inclosed therein and worked by an eccentric and governors or otherwise, and intended to act as an automatic variable cut-off or expansion valve.

The main valve is fitted in the cylindrical 20 valve-chest, the passages of which are placed in a diagonal or oblique form, the object of which is to quicken the variation of the expansion-valve; but we claim the right of using either diagonal or parallel passages, as the 25 main valve may be used either with or without the variable expansion-valve. The variable expansion-valve, being fitted inside the main valve, travels inside the same and cuts off the steam to engine by a rotary motion 30 given to it by the governor, to which provision is attached for adjustment at will, or by any other application or arrangement we may think fit to adopt to work the expansion-valve.

Reference is to be had to the accompanying 35 drawings, forming a part of this specification, in which similar letters of reference indicate corresponding parts in all the figures.

Figure 1 is a central sectional view of our 40 improved valve, representing the same as arranged in connection with the steam-chest of a cylinder, which steam-chest and cylinder are also shown in section, the view being taken in line *x x* of Fig. 4. Fig. 2 is a sectional view 45 of the steam-chest with the valve removed. Fig. 3 is a view of the inner or cut-off valve. Fig. 4 is an end view of the cylinder and steam-chest, and Fig. 5 is a cross sectional view taken 50 on line *y y* of Fig. 1.

Fig. 1 shows a section of cylinder and valve-

chest and main and cut-off valves through line *x x*, Fig. 4. The steam enters the valve-chest I by branch E, Fig. 2, thence into the cylindrical cut-off valve B, Fig. 1. After passing through cut-off valve B the steam enters the cylindrical main valve A, thence into the ports J to K into cylinder, and exhausting into port L in valve to port M in cylinder, as in the ordinary way. The valve-chest I is truly bored out to receive the main 55 valve A, which is made a perfect sliding fit. The cylindrical main valve A, Fig. 1, has a to-and-fro sliding motion imparted to it by spindle C, which is connected to rod worked by an eccentric on the main shaft. The cylindrical cut-off valve B, Fig. 1, is properly turned 60 to fit in main valve A, Fig. 1, which receives its sliding motion in a similar manner to the main valve A from a second eccentric on the main shaft, the rod of which is coupled to the 65 spindle F. The spindle F of cut-off valve B has a feather-key sunk in at N, and is secured to valve B by two collars and set-screws or taper pins. The arm X, Fig. 1, is cast on the valve chest cover, on which provision is 70 left for receiving brass bush Y, through which the spindle F travels to and fro. At this end of the spindle F there are two feather-keys, which pass through two seats in bush Y. The lever H, being secured to bush Y, when lifted 75 by the governor to which it is attached, gives the rotary motion to cut-off valve B, to which it gives the necessary lap over the oblique ports simultaneously with the sliding motion given to the same by the eccentric on the main 80 shaft.

Fig. 2 shows a section of the cylindrical valve-chest, and shows the oblique ports or passages O P, Fig. 2, which extend nearly half-way round the cylindrical valve-chest. 90 The valve-chest I, Fig. 2, is truly bored between T and U on the top and V and W on the bottom, and vice versa on the other side of the valve-chest, the rest portion of the valve-chest I being cored out to wider diameter to allow the steam to get at the back of the valve, so as to counterbalance the steam in front of it, and thus render the main valve 95 an equilibrium or truly balanced one.

Fig. 3 on the annexed drawings shows the 100

cut-off valve B. It will be seen that the back and front of the valve being of the same area and the steam being admitted inside the valve makes this valve also an equilibrium one.

5 This valve being of an oblique form, the rotary motion given to it by the governor increases the lap of the valve, thereby giving it the variable cut-off. When the governor-balls are down, the valve B cuts off steam at 10 three-quarters stroke, and when extended at full cuts off at one-quarter stroke, the rotary motion thus varying the cut-off from one-quarter to three-quarters stroke.

We do not claim a cylindrical cut-off valve 15 adapted to rotate within a slide-valve that works on a seat having diagonal ports.

What we claim is—

The combination of the following elements for the purpose of forming an automatic va-

riable cut-off or expansion valve, to wit: the 20 main slide-valve A, having the form of a hollow cylinder and provided with diagonal ports, the cylindrical cut-off valve B, constructed with diagonal passages and adapted to fit in said main valve, it also having both sliding 25 and rotary motions therein, and the cylindrically-bored steam-chest having the diagonal steam-ports, and means for operating both valves A and B, all arranged as shown and described.

ROLAND BENTLEY.
THOMAS FORD.
